US00D800908S

(12) **United States Design Patent** (10) **Patent No.:** **US D800,908 S**
(45) **Date of Patent:** **** Oct. 24, 2017**

(54) **PROSTHETIC VALVE ELEMENT**(71) Applicant: **MITRALTECH LTD.**, Or Yehuda (IL)(72) Inventors: **Ilia Hariton**, Zichron Yaakov (IL);
Boaz Harari, Ganey Tikva (IL); **Meni Iamberger**, Kfar Saba (IL); **Aviram Baum**, Tel Aviv (IL)(73) Assignee: **MITRALTECH LTD.**, Or Yehuda (IL)(***) Term: **15 Years**(21) Appl. No.: **29/573,863**(22) Filed: **Aug. 10, 2016**(51) LOC (10) Cl. **24-02**

(52) U.S. Cl.

USPC ..... **D24/155**(58) **Field of Classification Search**USPC **D24/155-157**

(57) **CLAIM**

The ornamental design for a prosthetic valve element, as shown and described.

DESCRIPTION

FIG. 1 is a perspective view from above of the prosthetic valve element embodying our new design;

FIG. 2 is a perspective view from the bottom thereof;

FIG. 3 is a front side view thereof, the right side, left side and

rear side views appearing the same;

FIG. 4 is a bottom view thereof; and,

FIG. 5 is a top view thereof.
